LAPPING MACHINE

Wallace H. Wood, Worcester, Mass., assignor to
Norton Company, Worcester, Mass., a corpora-
tion of Massachusetts

Application August 17, 1940, Serial No. 353,027

19 Claims.

(Cl. 51—67)

The invention relates to lapping machines, and more particularly to a machine for lapping a cylindrical work piece.

One object of the invention is to provide a simple and thoroughly practical lapping machine for cylindrical work pieces. Another object of the invention is to provide an automatically controlled machine for lapping a cylindrical portion on a work piece. Another object of the invention is to provide an automatically actuated lapping machine for simultaneously lapping a plurality of spaced portions on a work piece.

A further object of the invention is to provide a cylindrical type lapping machine with a reciprocable type lapping element for lapping the work surface while the work piece is rotated at a progressively increasing work speed in a manner to produce continually varying abrading lines on the surface of the work which are substantially parallel to the work axis at the start of the lapping operation and which are progressively increased in angular relation with the work axis until they approach a path at right angles thereto at the end of the lapping operation.

Another object of the invention is to provide a lapping machine for lapping a plurality of spaced portions on a rotatable work piece which is semi-automatic in operation and which is controlled by a single control lever. Another object of the invention is to provide a cylindrical type lapping machine in which a plurality of lapping heads are automatically moved toward and from a work piece, lapping sticks on each of the heads are automatically started reciprocating as the heads move toward the work piece, and in which the work rotation is initiated by the relative approaching movement of the lapping heads.

A further object of the invention is to provide a work driving mechanism which rotates the work at a slow rate of speed at the start of the lapping operation and the speed of which is automatically increased to a maximum at the end of the lapping operation, after which the lapping heads automatically recede and the work rotation is stopped. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

55 In the accompanying drawings, in which is

shown one of various possible embodiments of the mechanical features of the invention—

Fig. 1 is a front elevation of a lapping machine embodying this invention;

Fig. 2 is a right-hand end elevation of the lapping machine as shown in Fig. 1;

Fig. 3 is a fragmentary plan view of the lapping machine;

Fig. 4 is a diagrammatic showing of the hydraulic control system;

Fig. 5 is a fragmentary longitudinal sectional view, on an enlarged scale, through the headstock;

Fig. 6 is a fragmentary cross-sectional view, taken approximately on the line 6—6 of Fig. 5, through the headstock;

Fig. 7 is a fragmentary vertical sectional view, on an enlarged scale, taken approximately on the line 7—7 of Fig. 3, through one of the lapping heads;

Fig. 8 is a fragmentary vertical sectional view, taken approximately on the line 8—8 of Fig. 7 through one of the lapping heads;

Fig. 9 is a fragmentary cross-sectional view, taken approximately on the line 9—9 of Fig. 7, through the lapping head and its support;

Fig. 10 is a fragmentary vertical sectional view, taken approximately on the line 10—10 of Figs. 7 and 9;

Fig. 11 is a fragmentary sectional view, on an enlarged scale, taken approximately on the line 11—11 of Fig. 1;

Fig. 12 is a fragmentary sectional view, taken approximately on the line 12—12 of Fig. 11;

Fig. 13 is a fragmentary vertical sectional view through the gear mechanism for driving the motor operated rheostat for controlling the work piece; and

Fig. 14 is a fragmentary sectional view, on an enlarged sectional view through one of the lapping head fluid motors.

A lapping machine has been illustrated in the drawings in which a machine base 40 supports a work supporting table 41. A rotatable work support is provided on the table 41 including a headstock 42 and a footstock 43. The headstock 42 supports a rotatable headstock spindle 44 in bearings 45 and 46. The headstock spindle 44 is provided with a suitable driving mechanism such as, for example, a variable speed electric motor 47. The motor 47 is provided with a multiple V-groove pulley 48 which is drivingly connected by multiple V-belts 49 with a multiple V-groove pulley 50. The pulley 50 is fixedly supported on a shaft 51 which is journaled in bearing 52.

ings 52 and 53 in the headstock 42. A worm 53 is keyed to the shaft 51 and meshes with a worm gear 54 which is keyed to the headstock spindle 44.

5

Work drive

A suitable work driving mechanism is provided on the headstock 42 comprising a slidably mounted driving head 55 which is slidably keyed on the headstock spindle 44 (Fig. 5). The right-hand end of the driver 55 is formed with a recess 56 which is adapted to mate with a flange 57 formed on the end of a work piece, such as a crankshaft 58 to be lapped. The driving member 55 is also provided with a spring-pressed driving pin 59 which projects from the recess 56 and is arranged to engage a hole or aperture 60 in the flange 57 of the crankshaft 58. The work driver 55 is shown in an inoperative position (Fig. 5). When it is desired to drive and rotate a work piece, the driver 55 is moved toward the right (Fig. 5) to shift the driving pin 59 into engagement with the hole 60 and to shift the recess 56 into supporting engagement with the flange 57 of the crankshaft 58. A yoke-shaped member 61 is supported by a shaft 62 which is in turn supported by a bracket 63 which is formed integral with the headstock 42. The yoke 61 engages a pair of trunnions 64 and 65 which are formed integral with a semi-circular shaped member 66 which rides in a groove 67 formed in the work driver 55.

The work driver 55 is preferably automatically actuated in timed relation with the other mechanisms of the machine. An arm 68 is fixedly mounted on the shaft 62. The arm 68 is provided with a yoke-shaped end 69 which straddles and engages a groove 70 formed adjacent to the lower end of a piston 71. The piston 71 is slidably mounted in a cylinder 72, which is fixedly mounted relative to the headstock 42. The piston 71 is preferably provided with a central aperture 73. A compression spring 74 is contained within the central aperture 73 and is interposed between the upper end of the aperture 73 and an adjustable stud or stop screw 75 which is fixedly mounted on the headstock 42. The spring 74 normally tends to hold the piston 71 in its uppermost position with the work driver 55 in operative driving engagement with the flange 57 on the crankshaft 58 to be lapped.

When the fluid under pressure is admitted through a pipe 76 into a cylinder chamber 77, a downward movement of the piston 71 is obtained against the compression of the spring 74 which serves through the arm 68 to rock the shaft 62 and the yoke 61 in a counterclockwise direction (Fig. 5) to disengage the work driving member 55 to facilitate removal of a finish lapped work piece and the insertion of a new work piece to be lapped thereinstead.

Footstock

The other end of the crankshaft 58 is supported by the footstock 43 which is provided with a footstock center 80. The center 80 is carried by a rotatable spindle 81 which is journaled in bearings 82 and 83 within a hollow slidably mounted sleeve 84. The sleeve 84 is slidably keyed by means of a key 85 within an aperture 70 in the footstock frame 43.

A fluid pressure actuated mechanism is provided for moving the footstock center 80 rapidly to and from an operative position, that is, into or out of supporting engagement with a frusto-conical aperture 86 formed in the right-

hand end of the crankshaft 58. This mechanism comprises a fluid pressure cylinder 87 having a slidably mounted piston 88 contained therein. The piston 88 is connected to one end of a piston rod 89. The other end of the piston rod 89 is provided with an enlarged head 90 having an elongated slot 91 within which slides a slabbed-off pin 92. The pin 92 serves as a central pivotal connection between a pair of toggle levers 93 and 94, respectively. The toggle lever 94 is connected to the footstock frame 43 by means of a stud 95. The other end of the toggle lever 93 is connected by a stud 96 with a slidably mounted hollow sleeve 97 which slides within an aperture 98 within the sleeve 84. The sleeve 97 is held against rotation by means of a screw 99 which is carried by the sleeve 84 and which rides within an elongated slot formed in the sleeve 97. A spring 100 is contained within the sleeve 97 and is interposed between the end of an aperture in the sleeve 97 and a thrust collar 101.

When fluid under pressure is admitted through a pipe 102 into a cylinder chamber 103, the piston 88 is moved downwardly and the toggle levers 93 and 94 are moved from the full line position into the dotted line position 93a and 94a which serves to move the sleeve 97 toward the left (Fig. 4). This movement serves to compress the spring 100 and through the connecting parts above described moves the sleeve 84 and the footstock center 80 into operative engagement with the right-hand end of the crankshaft 58. During this movement fluid is exhausted from a cylinder chamber 104 through a pipe 105. The admission to and exhaust of fluid from the footstock operating cylinder 87 will be hereinafter described. This footstock is substantially identical with that shown in the prior U. S. Patent No. 2,117,960 dated May 17, 1938, to which reference may be had for details of disclosure not contained herein.

Lapping heads

The base 40 is provided with an upwardly extending column 110 which serves as a support for a plurality of lapping heads 111, 111a, 111b and 111c. The column 110 is provided with a pair of spaced longitudinally extending T-slots 112 and 113 which serve as guideways adjustably to support the lapping heads 111, 111a, 111b and 111c. Each of the lapping heads 111, 111a, 111b and 111c is provided with a supporting frame 114, 114a, 114b and 114c, respectively, which is provided with an integral projecting rib 115 which slides within the T-slot 112. The lapping heads 111, 111a, 111b, and 111c may be clamped in adjusted position on the column 112 by means of clamping T-bolts 116 and 117. The T-bolts 116 and 117 pass through holes or apertures in the frame 114 and are provided with heads which mate with the T-slots 112 and 113. By means of the clamping T-bolts 116 and 117, the heads 111 may be adjusted longitudinally in setting up the machine for a given lapping operation.

Each of the frames or brackets 114 is provided with a forwardly extending portion which serves as a support for a vertically adjustable plate 118. The bracket 114 is provided with a groove 119 in the sliding surface 120 which mates with a correspondingly shaped surface on the plate 118. The plate 118 is provided with a projecting guiding rib 121 which mates with the slot 119 so as to guide the plate 118 in a ver-

tical direction. The plate may be clamped in adjusted position on the bracket 114 by means of clamping screws 122 and 123 which pass through elongated slots 124 and 125 in the bracket 114 and are screw threaded into the plate 118. A vertically arranged adjusting screw 126 is carried by a boss 127 (Fig. 10) formed integral with the bracket 114 and serves to facilitate vertical adjustment of plate 118. The plate 118 serves as a support for a transversely adjustable bracket 130. The plate 118 is provided with a groove 131 which is engaged by a rib 132 formed integral with the bracket 130. Clamping screws 133 and 134 are passed through elongated slots 135 and 136, respectively, and are screw threaded into the plate 118 and serve to facilitate a transverse adjustment of the bracket 130.

Hydraulic lift—Lapping heads

In order to facilitate loading of work pieces into the machine and removal thereof after a lapping operation has been completed, it is desirable to provide a mechanism for raising and lowering the lapping heads 111, 111a, 111b and 111c to and from an operative position. This is preferably accomplished by means of a fluid pressure mechanism such as, for example, an individual fluid pressure piston and cylinder associated with each of the lapping heads. A fluid pressure cylinder 140 is formed integral with the bracket 130. The side face of the cylinder 140 is provided with a dovetailed guideway 141 which mates with a correspondingly shaped way formed on the lapping head 111 (Fig. 9). A piston 142 is slidably mounted in the cylinder 140 and is connected to one end of a piston rod 143. The upper end of the piston rod 143 is connected to a plate 144 mounted on the upper end of the lapping head 111 (Fig. 8). This raising and lowering mechanism for the lapping heads is identical, consequently details of each of the mechanisms have not been shown in the drawings although they have all been indicated in the hydraulic diagram shown in Fig. 4, like parts of each of the mechanisms being designated by the same numerals with the suffix a, b, or c.

It will be readily apparent from the foregoing disclosure that when fluid under pressure is admitted through a pipe 145, 145a, 145b, and 145c to the cylinder chambers above the pistons 142, 142a, 142b and 142c (Fig. 4), a downward movement of the pistons 142 and the lapping heads 111 will be obtained. During the downward movement of the lapping heads 111, fluid is exhausted from the cylinder chambers below the pistons 142, through pipes 146, 146a, 146b and 146c, respectively. Similarly, when fluid under pressure is reversed and passed through the pipes 146, 146a, 146b and 146c, the pistons 142 will be moved upwardly simultaneously to raise all of the lapping heads 111, 111a, 111b and 111c to an inoperative or loading position. The hydraulic system for controlling the admission of fluid under pressure through the pipes 145 and 146 will be hereinafter described. Each of the lapping heads 111 is provided with a lapping element preferably comprising a stick of bonded abrasive material such as, for example, the lapping sticks 150 and 151 (Fig. 7). The lapping sticks 150 and 151 are supported on a lapping stick holder 152 which is provided with oppositely extending trunnions 153 and 154 which are in turn pivotally supported in bearings carried by the side plates 155

and 156. The plates 155 and 156 are supported on an oscillatable arm 157 which is arranged to oscillate about the axis of the stud 158 as a pivot.

Lapping stick—Straight line motion

In order that a straight line motion may be imparted to the lapping sticks 150 and 151, a slight vertical movement of the oscillatable arm 157 and its supporting stud 158 is provided. A pair of spaced slides 159 and 160 are mounted on opposite ends of the stud 158 and are arranged to slide in parallel guide surfaces 161 and 162, respectively. The upper end of the oscillatable arm 157 carries a roller 163 which is mounted on a stud 164. The stud 164 is fixedly mounted on the oscillatable arm 157 and supports the roller 163 so that it engages a cam face 165 which is fixedly supported relative to the plate 144. The shape of the cam 165 is such that when the oscillatable arm 157 is oscillated, it will impart a straight line reciprocating movement of the lapping sticks 150 and 151. The roller 163 is normally held in operative engagement with the cam 165 by means of the fluid under pressure within the cylinders 140. A spring 166 is fastened at its upper end to the oscillatable arm 157 and at its lower end to an adjustably positioned stud 167 and serves to exert a downward force on the oscillatable arm 157 yieldably to maintain the lapping sticks 150 and 151 in operative lapping engagement with the work piece being lapped. A stop pin 168 carried by the lapping head 111 serves to limit the downward movement of the oscillatable arm 157. The stop stud 168 is arranged in the path of the pivot stud 158.

Fluid motor—Lapping stick reciprocation

A suitable power operated mechanism is provided for oscillating the arm 157 to reciprocate the lapping sticks 150 and 151 in operative engagement with the work piece to lap the same. In the preferred form, a self-contained fluid pressure motor is provided comprising a fluid pressure motor 170, 170a, 170b and 170c is provided on each of the lapping heads 111, 111a, 111b and 111c, respectively. Each of these motors comprises a cylinder 171 (Fig. 14) having a piston 172 slidably mounted therein. The piston 172 is connected by means of a piston rod 173 with the upper end of the oscillatable arm 157. A pilot valve 174 is slidably mounted within the motor casing 170. The pivot valve 174 is provided with a central bore or aperture which contains a slidably mounted shuttle type reversing valve 175. The pilot valve 174 is provided with a pair of adjustable collars 176 and 177 which are engaged by an upwardly extending portion of the oscillatable lever 157 by means of which the pilot valve is automatically shifted at the end of the stroke to shift the reversing valve and thus change the direction of oscillation of the lever 157 continuously to reciprocate the lapping sticks 150 and 151. Fluid under pressure is admitted through a pipe 178 into the valve mechanism to actuate the piston 172 as desired. An exhaust pipe 179 is provided whereby fluid is readily exhausted from the fluid motor. The collars 176 and 177 are preferably adjustably mounted on the valve stem so that the length of the oscillatory stroke of the arm 157 and also the reciprocating stroke of the lapping sticks 150 and 151, respectively, may be adjusted as desired. This hydraulic motor has not been described in detail in the present application since the details of the

motor are not considered to be a part of the present invention. Any standard motor, either hydraulic or otherwise, might be employed for this purpose. For details of disclosure not contained herein, reference may be had to my pending U. S. patent application Serial No. 237,654, filed October 29, 1938.

It is desirable automatically to start the reciprocatory movement of the lapping sticks 150 and 151 when the lapping head 111 is moved toward an operative position and similarly to stop the reciprocation thereof when the lapping head is moved to an inoperative position. To accomplish this desired result, a normally closed valve 180 is provided for each of the motors 170 in the pipe lines 178, 178a, 178b and 178c. The valve 180 may be opened by means of a pivotally mounted lever 181 having an actuating roller 182 at its lower end. In order that the valve may be automatically controlled by the approaching and receding movement of the lapping head 111, a cam 183 is adjustably mounted on the bracket 130 which supports the lapping head 111. A pair of screws which hold the cam 183 in adjusted position on the bracket 130 pass through elongated slots in the bracket, thus facilitating a slight transverse adjustment of the bracket to adjust the time of opening the valve 180. This adjustment is intended for use in setting up the machine to facilitate starting reciprocatory movement of all the heads at the same time. Each of the lapping heads 111 is provided with a similar construction and the corresponding parts are identified by the same reference numerals suffixed with the designations *a*, *b*, and *c*.

In order that the cycle of operation of the machine may be automatic it is desirable to provide an automatically actuated mechanism for starting the rotation of the work drive motor 47 in timed relation with the other parts of the machine. In the preferred form, it is desirable to start the rotation of the motor 47 when the lapping heads 111 are moved toward an operative position and similarly to stop the work drive motor when the heads are moved to an inoperative or loading position. A rock shaft 185 is supported at one end in a bearing 187 which is formed integral with the plate 118c. An intermediate bearing 188 is formed integral with the plate 118, thus serving as a support for the rock shaft 185. The rock shaft 185 is provided with a plurality of adjustably positioned arms 189, 189a, 189b and 189c. Each of the levers 189 is provided with an actuating roller 190 which is arranged in the path of a cam 191 which is adjustably mounted on the lapping head 111.

A pair of clamping screws pass through elongated slots in the cam 191 and are screw threaded into the lapping head 111. Cams 191a, 191b and 191c are adjustably mounted on lapping heads 111a, 111b and 111c, respectively. A downwardly extending arm 192 is mounted on the right-hand end of the rock shaft 185. A link 193 connects the arm 192 with the actuating lever 194 of a normally open limit switch 195. It will be readily apparent from the foregoing disclosure that when the heads 111, 111a, 111b and 111c are moved downwardly into an operative position, the cams 191, 191a, 191b and 191c will engage the rollers 190 and rock the shaft 185 in a counterclockwise direction (Fig. 4) which in turn serves to rock the lever 194 of the limit switch 195 in a clockwise direction (Fig. 4) to close the switch 195. The switch 195 is op-

eratively connected in a manner to be herein-after described to start rotation of the work driving motor 47. The cams 191, 191a, 191b and 191c are preferably adjusted in a vertical direction so that they all engage their respective 5 rollers 190 at substantially the same time.

It will, however, be readily apparent from the foregoing disclosure that the first cam 191 engaging the roller 190 serves to start a rocking movement of the rock shaft 185 on the downward movement of the lapping heads 111 to start closing the limit switch 195. Similarly, it will be readily apparent that as the lapping heads 111 move upwardly to an inoperative position, the last cam 191 to leave the roller 190 serves to allow the rock shaft 185 to be rocked to an inoperative position to again open the limit switch 195 and thereby stop the rotation of the work at the end of a lapping cycle. An arm 196 is mounted on the right-hand end of the rock shaft 185 (Fig. 3). The arm 196 is connected by means of a tension spring 197 to a bolt 198 which is clamped in adjusted position in the T-slot 113 (Fig. 1). When the last cam 191 raises out of contact with its roller 190, the released tension of the spring 197 serves to rock the rock shaft 185 in a clockwise direction so as to aid in opening the normally open limit switch 195, thus stopping the work driving motor 47.

Hydraulic system

30

A hydraulic or fluid pressure system is provided for supplying fluid under pressure to the various mechanism of the machine. A fluid reservoir 200 is provided in the base of the machine. 35 A motor driven fluid pressure pump 201 serves to pump fluid through a pipe 202 from the reservoir 200 and forces fluid under pressure through a pipe 203. Fluid under pressure in the pipe 203 passes through a pipe 204 to a manually operable main control valve 205 to be hereinafter described and also passes fluid under pressure through a pipe 206 to a progressively actuated, automatically controlled valve 207 which will also be hereinafter described. Fluid under pressure in the pipe 206 also passes through a pipe 208 which is connected with the pipes 178, 178a, 178b and 178c to supply fluid under pressure to operate the hydraulic motors 170, 170a, 170b and 170c. Fluid under pressure exhausting from the 45 motors 170, 170a, 170b and 170c passes through a pipe 209 which exhausts into the reservoir 200. 50

The progressively actuated control valve 207 is a piston type valve comprising a valve stem 210 having valve pistons 211, 212, 213 and 214 formed 55 integral therewith. The valve pistons 211, 212, 213 and 214 form valve chambers 215, 216, 217, 218 and 219. The progressive valve 207 serves to control the admission of fluid under pressure to the cylinders for raising and lowering the lapping heads 111, to the cylinder for actuating the footstock center 80 and also to the cylinder 72 for actuating the work driver 55. In the position of the valve 207 (Fig. 4), fluid under pressure passing through pipe 206 enters the valve chamber 217 and passes outwardly through a pipe 220 which connects with the pipes 146, 146a, 146b and 146c to admit fluid under pressure to the cylinder 140, 140a, 140b and 140c to raise all 60 of the pistons 142 and the lapping heads 111 to an uppermost or inoperative position. During this movement, fluid exhausting from the cylinders 140, 140a, 140b and 140c through the pipes 145, 145a, 145b and 145c exhausts through a pipe 221 which enters the valve chamber 216 and 65

passes outwardly into a valve passage 222 and out through a pipe 223 which connects with the exhaust pipe 209.

At the same time, fluid entering the valve chamber 217 (Fig. 4) passes outwardly through a pipe 225 into the cylinder chamber 104 to raise the piston 88, thus shifting the footstock parts including the center 80 to an inoperative position (Fig. 4). At the same time, fluid under pressure in the pipe 225 enters the cylinder chamber 77 in the cylinder 72 and moves the piston 71 downwardly which in turn serves through the parts as above described to rock the work driving member 55 toward the left to an inoperative or leading position. During the upward movement of the footstock piston 88, fluid within the cylinder chamber 103 exhausts through the pipe 102 into the valve chamber 216 and out through the valve passage 222, pipe 223, and the pipe 209 into the reservoir 200.

The main control valve 205 is preferably a piston type valve comprising the valve pistons 226, 227 and 228 forming valve chambers 229 and 230. In the position of the valve 205 (Fig. 4), fluid under pressure in the pipe 204 enters the valve chamber 230 and passes outwardly through a pipe 231. The pipe 231 is connected to an end chamber 215 of the valve 207 which serves to move the valve stem 210 toward the right (Fig. 4) into the position as illustrated. This position is at the end of the lapping cycle when the parts of the machine are in a loading position. During the movement of the valve stem 210 toward the right, fluid within the end chamber 219 exhausts through a pipe 232 into the valve chamber 229 in the valve 205 and passes into the valve passage 233 and out through a pipe 234 which connects with the exhaust pipe 209 to exhaust fluid into the reservoir 200. The valve 205 is preferably manually actuated to start a lapping cycle but is automatically shifted into a reverse position by means of an electrically controlled mechanism aided by a compression spring 235 which is contained within a central aperture 45 within the valve 205 and is interposed between the upper end of said aperture and an end cap on the lower end of the valve.

A manually operable control lever 238 is pivotally supported by means of a stud 239 on the front 50 of the machine base 40. The stud or rock shaft 239 is mounted in a suitable bearing 240 formed in an apron 241 which is fixedly supported on the base 40 of the machine. A downwardly projecting lever 242 is fixedly mounted on the inner end 55 of the shaft 239 (Fig. 11). The downwardly extending arm 242 carries a stud 243 which is connected to the upper end of a link 244. The lower end of the link 244 is connected by a stud 245 with the upper end of the valve piston 226. It 60 will be readily apparent from the foregoing disclosure (Fig. 4) that the arm 242 and link 244 serve as toggle levers for actuating the valve 205. When it is desired to start a lapping cycle, the lever 238 is moved in a counterclockwise direction 65 into position 238a (Fig. 4), which movement rocks the arm 242 into position 242a and the link 244 into position 244a, thus causing a downward movement of the valve pistons 226, 227 and 228. In the downward position of the valve 205, fluid 70 under pressure from the pipe 204 enters the valve chamber 229 and passes outwardly through the pipe 232 into the end chamber 219 to shift the valve stem 210 toward the left (Fig. 4).

Movement of the valve stem 210 toward the 75 left serves first to uncover the pipe 102 so that

fluid under pressure within the valve chamber 217 passes through the pipe 102 into the cylinder chamber 103 to cause a downward movement of the footstock piston 88, thus operating to move the footstock center 80 into operative engagement 5 with the cone-shaped aperture at the right-hand end of the work piece 58. At the same time, the valve piston 213 has moved a sufficient distance toward the left so that fluid within the chamber 77 of the cylinder 72 may exhaust through the 10 pipes 76 and 225 into the valve chamber 218 and out through the passage 222, the pipe 223, and exhaust pipe 209 into the reservoir 200. Exhausting of fluid from the cylinder chamber 77 releases 15 the compression of the spring 74 which serves to rock the shaft 62 and the yoke 61 to move the work driver 55 toward the right (Fig. 5) into operative engagement, with the driving pin 59 and the recess 56 in operative supporting engagement with the flange 57 on the left-hand 20 end of the work piece 58. If the pin 59 does not engage the aperture 60 in the flange 57, the spring back of the drive pin 59 will be compressed and when the headstock spindle 44 starts rotation, the driving pin 59 will drop into the hole 25 60 on the first rotation of the work driver head 55, thus drivingly engaging and driving the work piece 58.

When the control lever 238 is rocked in a counterclockwise direction to actuate the valve 205, the 30 downwardly extending arm 242 and the link 244 move just past a straight line position with a downwardly extending projection 246 on the arm 242 engaging the left-hand side face of the link 244 (Fig. 12) which serves as a stop to limit 35 the movement of the lever 238 and thereby serves to lock the arm 242 and the link 244 against the compression of the spring 235. As the control lever 238 and shaft 239 are swung in a counterclockwise direction to actuate the valve 205 to 40 initiate a lapping cycle, a downwardly extending arm 247 formed integral with the lever 238 engages an actuating plunger 248 of a normally open limit switch 249. The normally open limit switch 249 is electrically connected to cooperate 45 with the normally open limit switch 195 to aid in starting the work drive motor 47, the electrical circuit being arranged so that the work drive motor 47 is not started until both of the limit switches 249 and 195 are closed.

In order automatically to stop the lapping cycle after it has progressed to a predetermined extent, an electric solenoid 250 is operatively connected by means of a link 251 with a stud 252 carried by the arm 241. At the end of the lapping 55 cycle, energization of the solenoid 250 serves to move the link 251 toward the left (Fig. 4), which movement rocks the shaft 239 and breaks the toggle action between the arm 242 and the link 244, thus releasing the compression of the springs 60 235 which rapidly shifts the valve pistons 226, 227 and 228 into their uppermost position. The breaking of the toggle connection serves to withdraw the arm 247 from engagement with the plunger 248 of the limit switch 249, thus allowing 65 the limit switch to open, which through an electrical circuit serves to stop the work drive motor 47.

Interlock

It is desirable that the various mechanisms of 70 the machine as above described have sufficient time to function before the next succeeding mechanism operates. It is, therefore, desirable to provide an interlocking of the various mechanisms of the machine which may comprise a series of 75

stops which serve to limit the movement of the progressive control valve 207 when it is moved in either direction. These stops are interconnected with the various mechanisms so that after 5 a mechanism has performed its function, the valve stop will be automatically withdrawn, thereby permitting a further movement of the progressive control valve 207. This mechanism is somewhat similar to that disclosed in my prior U. S. 10 Patent No. 2,166,085 dated July 11, 1939.

A stop collar 255 is fixedly mounted on the rear end of the valve stem 210. The collar 255 is arranged to slide within an aperture formed within a casing 254 which is fixedly mounted on 15 the rear end of the casing of the valve 207. The casing 254 serves as a support for a plurality of spring-pressed stop plungers which are arranged intermittently to stop the movement of the valve stem 210 when it is moved either toward the rear 20 after a lapping operation has been completed or when the valve is moved forward after a new work piece has been loaded into the machine to start a lapping operation. As shown in Fig. 4, the valve 207 together with the other mechanisms 25 of the machine are shown in a loading position.

A stop plunger 256 is normally held in an operative position in the path of the stop collar 255 on the valve stem 210 by means of a spring 257. The stop 256 serves to stop the movement of the progressive control valve 207 when it is moved in a direction toward the left (Fig. 4). A similar stop plunger 258 is slidably supported in the casing 254 and is normally held in an operative position in the path of the stop collar 255 by means 35 of a spring 259.

The stop plunger 256 is connected by a link 260 with one end of a flexible cable, commonly known as a Bowden wire 261. The other end of the Bowden wire 261 is connected by means of a 40 stud 262 which is fixedly mounted on one arm of the yoked end 69 of the lever 68 which actuates the work driver 55. When the machine is in a loading position, fluid under pressure passing through the pipe 76 (Fig. 4) normally holds 45 the piston 71 in a downward position which, through the Bowden wire 261, serves to hold the stop plunger 256 in an operative position in the path of the stop collar 255 so that when the valve stem 210 is moved toward the left (Fig. 4), 50 it will move only until the collar 255 engages the stop plunger 256. During the movement of the valve stem 210 toward the left, the valve piston 213 opens the pipe 225 to the exhaust pipe line to exhaust fluid from the chamber 104 of the 55 footstock cylinder 87 and at the same time to exhaust fluid from the cylinder chamber 77 in the work drive control cylinder 72. When fluid in the chamber 77 is open to the exhaust line, the released compression of the spring 74 serves 60 to cause an upward movement of the piston 71 and at the same time an upward pull on the headstock end of the Bowden wire 261, which movement serves to cause a downward movement of 65 the stop plunger 256, thus facilitating a further movement of the valve stem 210 toward the left (Fig. 4). It will be readily apparent from the foregoing disclosure that the stop plunger 256 serves as an interlock to prevent admission of fluid under pressure to move the lapping head 70 111 to an operative position until the footstock center 80 has been moved into operative supporting engagement with the work piece 58 and the work driver 55 also moved into an operative position.

75 Similarly, the stop plunger 258 is provided to

stop the movement of the valve stem 210 in its movement toward the right so as to interlock the movement of the lapping heads 111 and the footstock center 80 so that the footstock center 80 cannot be withdrawn until the lapping heads 111 have been moved upwardly to an inoperative position. The stop plunger 258 is connected by a link chain 263 with one end of a rock arm 264 which is in turn pivotally supported by a stud 265. The stud 265 is fixedly supported on the 10 casing 254. A tension spring 266 is connected between one end of the rock arm 264 and a stud 267 carried by the casing 254 and serves to exert a pressure normally tending to hold the stop plunger 258 in operative position in the path of 15 the stop collar 255. The other end of the rock arm 254 is connected by means of a Bowden wire 268. The other end of the Bowden wire 268 is connected to the downwardly extending arm 192.

It will be readily apparent from the foregoing 20 disclosure that when the lapping heads 111, 111a, 111b and 111c are moved downwardly at the start of a lapping operation, the cams 191, 191a, 191b and 191c will engage rollers 190 to rock the arms 189 and the rock shaft 185 to rock the arm 192 25 in a counterclockwise direction, which movement closes the normally open limit switch 195 and at the same time exerts a pressure on the Bowden wire 268 so as to rock the rock arm 264 in a counterclockwise direction so that the released compression of the spring 259 moves the stop plunger 258 into an operative position in the path of the stop collar 255. In this position, when the valve stem 210 is moved toward the right from its extreme left-hand position, the stop plunger 258 35 will prevent further movement of the valve stem 210 toward the right until all of the lapping heads 111 have been raised to an inoperative position and the rock shaft 185 rocked in a clockwise direction by released compression of the spring 197 40 (Fig. 1), which movement serves to exert a pull on the Bowden wire 268 to withdraw the stop plunger 258. It will be readily apparent that the stop plunger 258 stops the valve stem 210 in a position 45 to prevent admission of fluid under pressure to the pipe 225, to the footstock cylinder 87 and the headstock work driver cylinder 72 to move them to an inoperative or a loading position until all of the lapping heads 111 have moved to an inoperative 50 position.

In order to produce a cylindrical surface of the desired quality, it is desirable to provide a variable speed work driving mechanism by which the rotation of the work may be progressively and continuously varied during the lapping operation. 55 The speed of the work rotation at the start of the lapping operation preferably serves a definite relationship with the reciprocatory speed of the lapping element so that the path of movement of individual grains of the bonded abrasive lapping sticks 150 and 151 will travel in a path at a slight angle to the axis of the work, namely, substantially parallel therewith. The work driving mechanism from the start of the operation is progressively and continuously increased while the speed 60 of reciprocation of the lapping sticks remains constant so that the path of movement of individual grains in the lapping sticks progressively and continuously changes from a path substantially parallel to the axis to a final path at substantially 65 parallel to the axis to a final path at substantially 70 right angles thereto.

In the preferred construction, the work driving motor 47 is preferably controlled by an automatically actuated rheostat mechanism such as, 75 for example, by a motor driven or operated rheo-

stat such as, for example, the motor operated switches, CR8490 manufactured by the General Electric Company. The motor operated switch unit comprises a rheostat member 270 which is provided with an actuating arm which is provided with a rotatable control arm 271 which is in turn automatically rotated by means of a variable speed electric motor 273. The electric motor 273 is connected by a reduction gear mechanism. The motor 273 is provided with a motor shaft 274 having formed integrally therewith a worm 275 which meshes with a worm gear 276. The worm gear 276 is rotatably supported on a stud 277 which is fixedly supported on a frame 278 which is supported on the rear of the column 110 of the machine. A small gear 279 is also rotatably supported on the stud 277 and is fixedly keyed to the worm 278. The gear 279 meshes with a large gear 280 which is rotatably mounted on a stud 281. The stud 281 is fixedly mounted on the frame 278. The stud 281 also supports a gear 282 which is arranged to rotate with the gear 280. The gear 282 meshes with a gear 283 which is supported on the rheostat control shaft 284. The motor operated rheostat switch 270 is connected to control the rotation of the work driving motor 47 so that at the first of the lapping cycle, the rotation of the work piece 58 will be at a relatively slow speed, which speed will be continuously and progressively increased until the work speed reaches a maximum at the end of the lapping cycle.

The speed of the motor 273 for driving the rheostat 270 is manually adjustable so that the cycle of operation may be readily controlled. A rheostat 285 is mounted within the machine base 40 and is manually controlled by means of a knob 286 projecting from the front of the machine base 40. By adjustment of the rheostat 285, the speed of rotation of the motor 273 may be varied as desired, thus providing a manual control for adjusting the duration of the lapping cycle.

The motor operated rheostat switch unit 270 is of an automatic reset type in which the variable speed reversible motor 273 rotates in one direction during the lapping operation and which is automatically reversed and rotated in the reverse direction after a lapping cycle has been completed to reset the rheostat for the next lapping operation. This motor driven rheostat is a standard unit manufactured by the General Electric Company and, therefore, it is not deemed necessary to illustrate the details of this motor driven rheostat switch.

A push button switch 290 is provided on the front of the machine base 40 for starting and stopping the fluid pressure pump motor 291. A push button switch 292 is also provided on the front of the machine base 40 for rendering the circuit controlling the work driving motor 47 operative.

A pair of work supporting or loading brackets 295 and 296 are provided on the table 41 for supporting a crankshaft 58 to be ground. These loading brackets comprise horizontally positioned surfaces whereby the crankshaft 58 may be positioned and rolled into alignment with the work driver and the footstock center 80.

The operation of this machine will be readily apparent from the foregoing disclosure. Assuming the various mechanisms of the machine to have been previously adjusted, a crankshaft to be lapped is positioned on the loading brackets 295 and 296. The push button switches 290 and 292 are actuated to start the pump drive motor 291 and to render the work drive motor 47 operative.

The work piece, such as the crankshaft 58, is then moved transversely into axial alignment with the work driver 55 and the footstock center 80. The control lever 238 (Fig. 1) is then moved in a counterclockwise direction, which movement shifts the valve 205 downwardly. This movement of the control lever closes the limit switch 249 and at the same time admits fluid under pressure through the pipe 232 into the right-hand end chamber 219 of the valve 207 to shift the progressive control valve 207 so as to start the lapping cycle.

During the first part of the movement of the valve 207 toward the left (Fig. 4), fluid under pressure is admitted to the cylinder chamber 103 of the footstock actuated cylinder and also to the chamber 11 of the headstock work driver cylinder 42 simultaneously to move the work driver 55 and the footstock center 80 into operative supporting engagement with the opposite ends of the crankshaft 58. The downward movement of the piston 17 in the headstock cylinder 42 serves to draw the stop plunger 256, thus allowing the progressive control valve to complete its movement toward the left (Fig. 4), which movement serves to admit fluid under pressure to the cylinder chamber above the pistons 142, 142a, 142b and 142c to cause a downward movement of the pistons so as to move the lapping heads 111, 111a, 111b and 111c downwardly into an operative position with the lapping sticks 150 and 151 in operative engagement with the spaced portions of the shaft to be lapped. During the downward movement of the lapping heads 111, the cams 191, 191a, 191b and 191c engage rollers 190, 190a, 190b and 190c. The first cam to engage its respective roller rocks the shaft 185, thus closing the normally open limit switch 195 which starts the rotation of the work driving motor 47 at a slow rate of speed. The downward movement of the lapping heads 111, 111a, 111b and 111c also serves through the rollers 182, 182a, 182b and 182c moving into engagement with the cams 183, 183a, 183b, and 183c to open the valves 180, 180a, 180b and 180c, respectively. The opening of these valves serves to admit fluid under pressure to the fluid motors 170, 170a, 170b and 170c simultaneously to produce a reciprocatory movement of all of the lapping sticks.

As the lapping operation proceeds, the speed of the driving motor 47, under the control of the motor driven rheostat 270 is gradually and progressively increased to gradually and progressively increase the speed of rotation of the crankshaft 58. At the start of the lapping operation, the lines of travel of the individual abrasive grains as produced by the combined reciprocatory stroke of the lapping sticks and the rotation of the work piece 58 produces lines on the work piece which are substantially parallel to the axis of rotation of the shaft 58. As the speed of the work piece 58 is gradually and progressively increased, these lines produced by individual abrasive grains of the lapping sticks gradually change their direction until at the end of the lapping cycle, these lines approach a path normal to the axis of rotation of the shaft. This gradual increase of speed provides an ever changing path of the abrasive grains in the lapping sticks, thus providing a complete break-up motion of the abrading action of the sticks to produce an ultra-fine finish on the periphery of the work piece being lapped.

After the motor driven rheostat has completed its cycle and brought the work drive motor 47 up

to the maximum speed, the lapping operation is stopped. The solenoid 250 is energized which breaks the toggle action between the levers 242 and 244 again shifting the valve 205 upwardly to admit fluid under pressure through the pipe 231 into the cylinder chamber 215 at the left-hand end of the progressive control valve 207 which serves to stop the lapping cycle. The valve 207 can only move until the stop collar 255 engages the stop plunger 258. This movement of the valve serves to admit fluid to the cylinder chamber below the pistons 142, 142a, 142b and 142c to cause an upward movement of all of the lapping heads to their inoperative position. Upward movement of the lapping heads serves to close all of the valves 180 to stop the reciprocatory movement of the lapping sticks. After the last lapping head has moved upwardly so that all of the cams 191 have withdrawn from contact with the rollers 190, the released compression of the spring 197 will rock the shaft 185 in a clockwise direction (Fig. 4) to withdraw the stop plunger 258, thus allowing the progressive control valve 207 to complete its movement toward the right (Fig. 4).

This final movement of the valve 207 serves to admit fluid under pressure through the pipe 225 into the footstock cylinder chamber 104 to move the footstock center 80 to an inoperative position and at the same time fluid under pressure is admitted to the headstock cylinder 77 to cause a downward movement of the piston 71 which in turn serves to withdraw the work driver 55 to an inoperative position so that the work piece 58 which has been lapped may be readily removed from the machine and replaced by a new piece to be lapped. This cycle of operation may then be continued. It should be noted that the cycle of operation is semi-automatic in operation, it being merely necessary for the operator to start the cycle by shifting the control lever 238, after which the various mechanism of the machine automatically go through their cycle of operation until the shaft has been lapped, after which the cycle is automatically stopped.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a rotatable work support, a work driving mechanism to rotate a work piece supported thereon, a lapping head including a reciprocable lapping element, means including a motor to reciprocate said lapping element, means to stop and start said motor, means including a motor to move said head to and from an operative position, means including a control lever to control said latter motor, and means actuated by movement of said head to an operative position to start said lapping element reciprocating motor and to start said work driving mechanism.

2. In a lapping machine having a rotatable work support, a work driving motor to rotate a work piece supported thereon, a lapping head including a reciprocable lapping element, means including a motor to reciprocate said lapping ele-

ment, means to stop and start said motor, means including a motor to move said head to and from an operative position, means including a control lever to control said latter motor, and means actuated by movement of said head to an operative position to start said lapping element reciprocating motor and to start said work driving motor.

3. In a lapping machine having a rotatable work support, means to rotate a work piece supported thereon, a lapping head including a reciprocable lapping element, means including a motor to reciprocate said lapping element, means to start and stop said motor, means including a motor to move said head to and from an operative position, means including a control lever to control said latter motor, means actuated by movement of said head to an operative position to start said lapping element reciprocating motor, and means actuated by movement of said head to an operative position to start said work driving mechanism.

4. In a lapping machine having a rotatable work support, means including an electric motor to rotate a work piece supported thereon, a lapping head including a reciprocable lapping element, means including a fluid motor on said head to reciprocate said lapping element, a stop and start valve to control said fluid motor, means including a fluid pressure piston and cylinder to move said head to and from an operative position, a control lever and valve to control said piston and cylinder, means including a cam actuated by movement of the head toward an operative position to actuate the stop and start valve to start reciprocation of the fluid motor and the lapping element reciprocation, and means including a limit switch actuated by movement of the lapping head toward an operative position to start said electric motor so as to rotate a work piece.

5. In a lapping machine having a rotatable work support, means including a variable speed mechanism to rotate a work piece supported thereon, a lapping head including a reciprocable lapping element, means including a motor to reciprocate said lapping element, means to stop and start said motor, means including a motor to move said head to and from an operative position, means including a control lever to control said latter motor, means actuated by movement of said head to an operative position to start said lapping element reciprocating motor, and means actuated by movement of said head to an operative position to start said variable speed work drive mechanism.

6. In a lapping machine having a rotatable work support, means including a variable speed electric motor to rotate a work piece supported thereon, a motor driven variable speed rheostat to control said motor automatically to increase the speed of the work drive motor from a slow speed at the start of the lapping operation to a maximum speed at the completion of a lapping cycle, a lapping head including a reciprocable lapping element, means including a motor on said head to reciprocate said lapping element, means to move said head toward and from an operative position, and means actuated by and in timed relation with movement of the head to an operative position to start said fluid motor so as to reciprocate the lapping element and to start said rheostat and thereby start the work drive motor to rotate the work piece.

7. In a lapping machine having a rotatable

- work support, means including a variable speed electric motor to rotate a work piece, a motor driven variable speed rheostat to control said motor, a lapping head including a reciprocable lapping element, means including a fluid motor on said head to reciprocate said lapping element, a fluid pressure operated piston and cylinder to move said head toward and from an operative position, and means actuated by and in timed relation with movement of the head to an operative position to start said fluid motor so as to reciprocate the lapping element and to start said rheostat and thereby start the work drive motor to rotate the work piece.
8. In a lapping machine having a rotatable work support, means including a variable speed electric motor to rotate a work piece supported thereon, a motor driven variable speed rheostat to control said motor, a lapping head including a reciprocable lapping element, means including a fluid motor on said head to reciprocate said lapping element, a fluid pressure operated piston and cylinder to move said head toward and from an operative position, and means actuated by and in timed relation with movement of the head to an operative position to start said fluid motor so as to reciprocate the lapping element and to start said rheostat and thereby start the work drive motor to rotate the work piece, said rheostat serving to start the work drive motor at a relatively slow speed and automatically and progressively to increase the work speed as the lapping operation proceeds.
9. In a lapping machine having a rotatable work support, means including an electric motor to rotate a work piece supported thereon, a plurality of spaced lapping heads arranged simultaneously to lap spaced portions on a cylindrical work piece, a reciprocable lapping element on each head, a fluid motor on each head to reciprocate the lapping element, a start and stop valve on each head to control said motor, means including an independent piston and cylinder to move each head to and from an operative position, an independent adjustably mounted cam associated with each head to open and close the start and stop valve when the heads are moved to and from an operative position so as to control the reciprocation of said lapping elements, and a manually operable control valve simultaneously to control the admission to and exhaust from each of the lapping head moving cylinders.
10. In a lapping machine as set forth in claim 9, the combination with the parts and features therein specified, of means including a limit switch to start the work drive motor, means including a rock shaft to actuate said limit switch, and means including an adjustably mounted cam on each lapping head which are arranged to rock said shaft to close said switch and start the work drive motor when the heads are moved to an operative position.
11. In a lapping machine as set forth in claim 9, the combination with the parts and features therein specified, of means including a limit switch to start the work drive motor, means including a rock shaft to actuate said limit switch, and means including an adjustably mounted cam on each lapping head which are arranged to rock said shaft to close said switch and start the work drive motor when the heads are moved to an operative position, said parts being arranged so that the first cam to rock said shaft serves to start the work drive motor.
12. In a lapping machine as set forth in claim 9, the combination with the parts and features therein specified, of means including a normally open limit switch to start the work drive motor, means including a rock shaft to actuate said limit switch, a spring normally to hold said shaft to maintain said switch open, and means including an adjustable cam on each lapping head which are arranged to rock said shaft to close said switch and start the work drive motor when the heads are moved to an operative position.
13. In a lapping machine as set forth in claim 9, the combination with the parts and features therein specified, of means including a normally open limit switch to start the work drive motor, means including a rock shaft to actuate said limit switch, a spring normally to hold said shaft to maintain said switch open, and means including an adjustable cam on each lapping head which are arranged to rock said shaft to close said switch and start the work drive motor when the heads are moved to an operative position, said parts being arranged so that the movement of the last head to an inoperative positive position serves to release the tension of said spring to rock the shaft and open the limit switch so as to stop the work drive motor.
14. In a lapping machine having a base, a rotatable work support thereon including a headstock having a work driver and a footstock having a center, a fluid motor to move said work driver to and from an operative position, a fluid motor to move said footstock center to and from an operative position, means including an electric motor to rotate said work driver, a lapping head having a reciprocable lapping element, means including a fluid motor on said head to reciprocate said lapping element, means including a fluid motor to move said lapping head to and from an operative position, means including a switch actuated by and in timed relation with movement of said lapping head to an operative position to start said electric motor to rotate the work driver, and means including a manually operable control valve simultaneously to admit fluid to the work driver and footstock center fluid motors to move the driver and center into operative engagement with a work piece and thereafter to admit fluid under pressure to move the lapping head to an operative position.
15. In a lapping machine as set forth in claim 14, the combination with the parts and features therein specified, of a manually operable cycle valve, a fluid pressure actuated, progressively moved valve, said latter valve being arranged to control the admission of fluid under pressure to the work driver fluid motor, the footstock center fluid motor and the lapping head positioning motor, and a stop to limit the movement of the progressive valve in one direction to prevent admission of fluid under pressure to the work driver and footstock fluid motors until the lapping head is in an operative position.
16. In a lapping machine as set forth in claim 14, the combination with the parts and features therein specified, of a manually operable cycle valve, a fluid pressure actuated, progressively moved valve, said latter valve being arranged to control the admission of fluid under pressure to the work driver fluid motor, the footstock center fluid motor and the lapping head positioning motor, a stop to limit movement of the progressive valve in one direction, and means actuated by movement of said lapping head to an inoperative position to withdraw said stop, thereby preventing withdrawal of the work driver.

and footstock center until the lapping head is moved to an inoperative position.

17. In a lapping machine as set forth in claim 14, the combination with the parts and features 5 therein specified, of a manually operable cycle valve, a fluid pressure actuated, progressively moved valve, said latter valve being arranged to control the admission of fluid under pressure to the work driver fluid motor, the footstock center 10 fluid motor and the lapping head positioning motor, and a stop to limit the movement of the progressive valve in one direction to prevent admission of fluid under pressure to the lapping head actuating cylinder until the work driver 15 and footstock center are in an operative position.

18. In a lapping machine as set forth in claim 14, the combination with the parts and features 10 therein specified, of a manually operable cycle valve, a fluid pressure actuated, progressively 15 moved valve, said latter valve being arranged to control the admission of fluid under pressure to the work driver fluid motor, the footstock center 20

fluid motor and the lapping head positioning motor, a stop to limit the movement of the progressive valve in one direction, and means actuated by movement of the work driver into an operative position to withdraw said stop, thereby 5 preventing movement of the lapping head toward an operative position until the work driver and footstock center are in an operative position.

19. In a lapping machine as set forth in claim 14, the combination with the parts and features 10 therein specified, of a variable speed electric motor to rotate the work driver, a motor driven variable speed rheostat to control said motor, said rheostat serving to start the work drive motor at a relatively slow speed and automatically and progressively to increase the work speed to a maximum at the end of a lapping cycle, and means including a solenoid which is actuated when the work reaches its maximum speed to shift the manually operable control valve to 20 terminate a lapping cycle.

WALLACE H. WOOD.
